United States Patent Office.

EDWARD A. HYDE, OF ANN ARBOR, MICHIGAN.

Letters Patent No. 91,849, dated June 29, 1869.

IMPROVEMENT IN PNEUMATIC DENTAL PLUGGERS.

The Schedule referred to in these Letters Patent and making part of the same.

To all whom it may concern:

Be it known that I, EDWARD A. HYDE, of the city of Ann Arbor, county of Washtenaw, and State of Michigan, have invented a new and improved apparatus for the purpose of filling teeth, which I call the Pneumatic Dental Plugger; and I do hereby declare that the following is a full and exact description of the construction and operation of the same, reference being had to the accompanying drawings, and to the letters of reference marked thereon, making a part of this specification, wherein—

Figure 1 is a perspective view of the whole apparatus, showing the connection of the pedal-cylinder, by means of a flexible pipe, with the handle.

Figure 2 is a sectional view of the handle, with plugging-tool inserted.

Figure 3 is a sectional view of the same, showing the constituent parts, separated one from the other.

Figure 4 is a top view of the cap D.

Figure 5 is a side view of the socket for the shank of the plugging-tool.

Figure 6 is a top view of the said socket.

Figure 7 is a top view of the elastic cushion, which is set in the cap D.

A is the cylinder forming the tool-handle.

B is the plugging-tool.

C is the socket for the shank of the tool, over which the cap D sets, fastened by the screw E, which is set into the peripheral groove F.

G is the elastic cushion, against which the lug H on the shank rests, for the purpose of giving an elastic blow, and for throwing the tool back after each blow.

I is the piston or hammer, which slides in the cylinder or handle A.

K is a swivel-joint, at the bottom of the handle A, over which the flexible pipe sets, and which allows the handle to be turned freely. The axis of the swivel also limits the recoil of the hammer I.

The air-holes L L permit the entrance and escape of air between the piston and base of the tool.

M is the base of the pedal-apparatus.

N N are two standards, for supporting the driving-wheel O and the fly-wheel P.

Q is the pedal.

R is the condensing and rarefying-cylinder.

S is the piston, reciprocated by the crank-pin in the fly-wheel P, the said crank-pin being set in an eccentric, which is bedded near the centre of the fly-wheel.

T is an air-passage from the cylinder R to the flexible pipe U, whose top end sets over the swivel K.

V is a channel in the cap D, to allow the entrance of the lug H on the tool-shank.

W is a recess in the socket C, in which the lug H rests, to prevent the tool from turning.

X is a groove in the cap D, in which is set the elastic cushion G.

Y is a channel in the elastic cushion G, corresponding with and always opposite the channel in the cap D, and for the same purpose.

Z is a short tube, inserted in the bottom of the cylinder A, and is the axis of the swivel K.

The manner of operating the invention is as follows, to wit:

Turn the cap D until the screw E prevents its turning further. The channels V Y are now opposite the recess W, allowing the plugging-point to be inserted, the lug H passing through the channels V Y into recess W. Now, by turning the cap D in the opposite direction, the channels V Y are no longer opposite the lug H, and the plugging-tool is fastened. By working the pedal Q, the piston S is made to reciprocate, whereby the air contained in the two cylinders and the connecting-pipe is alternately condensed and rarefied. This condensation and rarefaction of the contained air cause the hammer I to reciprocate; the pressure of the condensed air causing the forward stroke, and atmospheric pressure causing the recoil of the hammer. The momentum of the hammer being imparted to the plugging-tool, any required metal may be condensed into the cavities of teeth by pressing the tool against the inserted metal.

As many as four hundred blows per minute are practicable for the operator and easy for the patient. By the use of this invention, from one-half to three-fourths of the operator's time is saved; the use of valves is entirely dispensed with, also the use of springs; the size and weight of the handle are reduced, and the liability of getting out of order overcome.

What I claim, and desire to secure by Letters Patent, is—

1. The tool-handle or cylinder carrying the piston or hammer, connected by means of a flexible pipe with the condensing and rarefying-cylinder and its piston, the said last cylinder and piston operating a column of air, without the use of a valve or spring, to produce reciprocation of the hammer, substantially as described.

2. The plugging-tool, provided with a lug for securing it in the socket, and to prevent its rotation, substantially as described.

3. The elastic cushion G, by which an elastic blow is secured, and the tool carried back to its normal position, substantially as described, and for the purpose set forth.

4. In combination with the cylinder A and the flexible pipe U, the swivel-joint K, substantially as described, and for the purpose set forth.

5. The recessed socket C and the slotted cap D, the latter provided with the groove X, the said parts being adapted to secure the tool B within the handle, and lock the same in fixed position, substantially as described.

6. In combination with the subject-matter of the first claim, the pedal-apparatus, arranged as shown, whereby a rapid and regular reciprocation is given to the piston or hammer, all substantially as hereinbefore set forth.

EDWARD A. HYDE.
